UNITED STATES PATENT OFFICE.

ADOLPH O. GOLDSTEIN, OF SANTA CRUZ, CALIFORNIA.

DESIGN FOR A COMBINED CASING AND BASE FOR AN ICE SHAVER.

Application filed September 26, 1927. Serial No. 23,558. Term of patent 14 years.

To all whom it may concern:

Be it known that I, ADOLPH O. GOLDSTEIN, a citizen of the United States of America, residing at Santa Cruz, in the county of Santa Cruz and State of California, have invented a new, original, and ornamental Design for a Combined Casing and Base for an Ice Shaver, of which the following is a specification, reference being had to the accompanying drawing, forming a part thereof.

Figure 1 is a side elevation of the article showing my new design, and

Figure 2 is a top plan view of the same.

I claim:—

The ornamental design for a combined casing and base for an ice shaver, substantially as shown.

ADOLPH O. GOLDSTEIN.
